UNITED STATES PATENT OFFICE.

EDWARD VROOM, OF OSSINING, NEW YORK, ASSIGNOR TO WESTERN ELECTRIC COMPANY, INCORPORATED, OF NEW YORK, N. Y., A CORPORATION OF NEW YORK.

LOOP ANTENNA.

Application filed May 26, 1924. Serial No. 716,046.

This invention relates to loop antennæ.

An object of this invention is to provide a loop antenna which is simple in construction, combining great strength and rigidity with a minimum of weight so that the cost thereof is reduced to a minimum.

Another object of the invention is to provide a loop antenna wherein symmetry of the physical parts is secured.

Another object is to provide a loop antenna which may be completely wound before its assembly with the base structure.

A feature of the invention relates to an improved portable, rotatable loop antenna, whereby the conductors of the loop are held in equal spacing relation in tension. The antenna of this invention comprises a light frame structure which is formed by the intersection of a plurality of polygons so arranged with respect to one another that each side of each polygon intersects two sides of every other polygon. Upon this structure is wound the antenna loop which consists of a plurality of equally spaced turns of a continuous conductor wound in solenoidal form. Attached to the intersecting polygons at their apices are flat blocks of insulating material, preferably micarta, which project equal distances beyond the apices. These plates are provided for spacing and supporting the antenna conductors. Reference may now be had for a more comprehensive idea of the nature of the invention to the accompanying drawings in which Fig. 1 is a front view of the assembled antenna showing the preferred form of this invention.

Fig. 2 is a perspective, portional view showing the antenna after it has been wound and before attachment to the rotatable pivot.

Fig. 3 is an apex of one of the polygons illustrating the spacing of the insulated block attached thereto.

Fig. 4 is a side view of the lower apex of one of the polygons after attachment to the rotating pivot.

In Fig. 5 is illustrated the double notched joint between the intersecting sides of the polygons.

Referring particularly to Fig. 1, continuous conducting strands 1 of any suitable wire are wound in equally spaced turns upon a frame 2. This frame comprises two intersecting polygons preferably triangles 3 and 4, the arms thereof being of some insulating material such as beech or maple wood. The

arms of these triangles may be joined at the vertices in any suitable manner. It will be noted that each arm of each triangle intersects two arms of the other triangle and at each intersection a double notched joint 6 is formed between the two arms. Since the arms intersect at an oblique angle it is necessary to provide a beveled notch joint such as shown in detail in Fig. 5. The arm is provided with a notch 7 having a depth equal to one-half the breadth of the arm and the notch being beveled in such a way that when the two arms are joined the angle formed thereby will give the complete structure a symmetrical appearance. At each apex is mounted a block of insulating material 13 having grooves 24 in its outer edge for the passage of conductors 1. This block is arranged symmetrically with respect to arm 21 and is of much greater length than the width of arm 21 so that there will be considerable overhang. It is secured to the arm 21 at its center by means of screws 23 in such a way that it projects slightly beyond the end of the arm so that the conductors of loop 1 which are spaced at equal distances from each other by grooves 24 are not in contact with any part of the frame structure. This structure may be arranged for mounting on a rotatable base by providing an insulating block 8 extending from the mid point of the lower arm of triangle 3 to the lower apex of triangle 4. This block may be secured to the lower arm of triangle 3 by a wood screw 9. The joint made between block 8 and the lower apex of triangle 4 may be better understood by referring to Fig. 2.

The arms 10 and 11 of triangle 4 are provided with beveled ends which are firmly secured to opposite sides of block 8 by any suitable fastening means such as nails 12. In the lower portion of block 8 is contained a groove wide enough to admit the insertion of insulating block 13. The depth of this groove is large enough to permit block 13 to extend a short distance beyond the lower end of block 8. Screws 14 are provided for securing blocks 8 and 13 together. A pivot 15 has its upper portion of the same cross section as block 8 and its lower portion circular in cross section to permit rotation when inserted in the round hole of base 16. It is noted that on the two opposite sides of the upper portion are fork shaped metal members 17. The

prongs 18 of each of these members are so spaced as to permit block 13 to fit snugly between them. The metal prongs 18 contain round holes 19 located at a distance from the upper edge of block 15 such that when they coincide with screw holes 20 there is ample space between the lower edge of block 13 and the upper edge of block 15 to prevent the conductors of loop 1 from touching block 15.

The lower portion of block 15 being circular in form is loosely inserted into a circular hole in any suitable base 16 so that the whole structure may rotate freely.

15 A loop antenna such as is above described may be successfully employed wherever loop antennæ are desired.

Although the principles of this invention have been illustrated and described in connection with certain specific structures, it is not intended that the present disclosure is to be limited thereby but only in as far as pointed out in the following claims.

What is claimed is:

- 25 1. A loop antenna, comprising a frame having a number of supporting arms arranged to form two similar polygons, each polygon comprising an equal number of arms joined together to form a closed figure, the polygons being so arranged that each arm of each polygon intersects and is secured to at least two arms of the other polygons, and a number of turns of an electrical conductor wound thereon.
- 30 2. A loop antenna, comprising a frame having arms arranged to form two triangles, each triangle being formed by joining three

arms together to form a closed figure, the said triangles being superimposed to form a six pointed figure in which each arm of one triangle intersects and is secured to two arms of the other triangle, and a number of turns of an electrical conductor wound thereon.

3. A loop antenna consisting of a number of turns of an electrical conductor wound upon a frame, said frame comprising supporting arms arranged to form two similar triangles superimposed to constitute a symmetrical six pointed figure, each arm of said frame being substantially tri-sected by and secured to two other arms.

4. A loop antenna including a loop conductor and a frame for supporting the turns of the loop, said frame comprising arms arranged to form two similar triangles, said triangles being overlapped to constitute a six pointed symmetrical figure, each arm of each of said triangles intersecting and being secured by interlocking connections to two arms of the other triangle.

5. A loop antenna including an electrical conductor, a frame upon which the turns of the conductor are wound, said frame comprising a number of arms joined together to form two triangles superimposed so as to constitute a symmetrical six pointed figure, a base having a rotatable element and means for connecting said rotatable element to said frame at one of said points.

In witness whereof, I hereunto subscribe my name this 26 day of May A. D., 1924.

EDWARD VROOM.
